UNITED STATES PATENT OFFICE

102,101

DESIGN FOR AN AUTOMOBILE HEATER

Carl H. Will and Henry W. Fink, Minneapolis, Minn., assignors to Tropic-Aire, Incorporated, Minneapolis, Minn., a corporation of Delaware

Application June 29, 1936, Serial No. 63,574

Term of patent 3½ years

To all whom it may concern:

Be it known that we, Carl H. Will and Henry W. Fink, citizens of the United States, residing at Minneapolis, in the county of Hennepin and State of Minnesota, have invented a new, original, and ornamental Design for an Automobile Heater, of which the following is a specification, reference being had to the accompanying drawing, forming part thereof, and in which

Figure 1 is a front perspective view of an automobile heater embodying our design; and

Figure 2 is a rear perspective view thereof.
We claim:

The ornamental design for an automobile heater as shown.

CARL H. WILL.
HENRY W. FINK.
